UNITED STATES PATENT OFFICE.

GEORGE S. MANUEL, OF TURLOCK, CALIFORNIA.

DRAWING-BOARD.

No. 858,194.

Specification of Letters Patent.

Patented June 25, 1907.

Application filed September 24, 1906. Serial No. 336,034.

To all whom it may concern:

Be it known that I, GEORGE S. MANUEL, a citizen of the United States, residing at Turlock, in the county of Stanislaus and State of California, have invented certain new and useful Improvements in Drawing-Boards; and I do hereby declare the following to be a full, clear, and exact description of the invention, such as will enable others skilled in the art to which it appertains to make and use the same.

This invention relates to drawing boards, and has for an object to provide a board embodying improved means for compensating for expansion and contraction.

A further object of the invention is to provide a drawing board composed of a plurality of strips rigidly secured side by side and with improved means binding their ends whereby a lateral expansion and contraction of the strips is permitted.

A further object of the invention is to provide in a drawing board a body composed of a plurality of plane strips rigidly connected at their adjacent edges and provided with tongue and groove connection with end cleats and with improved means permitting a lateral movement of the body portion relative to the end cleats.

With these and other objects in view, the invention comprises certain other novel constructions, combinations and arrangements of parts, as will be hereinafter fully described and claimed.

In the drawings:—Figure 1 is a view in plan of the improved drawing board with portions broken away to more clearly illustrate the structure. Fig. 2 is a view of the improved drawing board in longitudinal edge elevation. Fig. 3 is a view of the improved drawing board in transverse edge elevation.

Like characters of reference designate corresponding parts throughout the several views.

The improved drawing board forming the subject-matter of this application comprises a plurality of plane strips of board or like material 10 rigidly secured together at their adjacent edges by any approved means as the dowels 11. The associated strips 10 are provided along their ends with tongue and groove connection here shown as the tongues

12 upon which tongue are disposed end cleats 13 having a groove fitting upon the tongue 12 of the boards. At similar ends the cleats 13 are rigidly secured to one of the strips 10 as by the use of glue represented at 14 or screws 15, or both such means whereby the cleats 13 are rigidly secured to said strip at or near one outer edge. The strip 10 upon the opposite side is provided with an opening 15' extending longitudinally therethrough and wider in the direction of the width of the board than in a direction laterally of the board, whereby a slot is formed through which is inserted a 65 rod or bolt 16 having its opposite ends extend through the end cleats 13 and provided with heads 17 preferably counter-sunk as within the recesses 18.

It will be seen that the cleats 13 secured at 70 one end only to one side of the body of the drawing board permit the board to contract and expand under the action of the climate, or for other reasons, and that such expansion and contraction is permitted by the groove 75 15 within which is disposed the rod 16 and that the width of the body of the board may vary relative to the length of the cleats 13.

What I claim is:—

1. In a drawing board, a plane body provided with an elongated opening extending longitudinally through one edge, cleats disposed transversely across the ends of the body and secured thereto at the edge opposite the elongated opening, and a bar extending through the elongated opening and connecting the cleats.

2. A drawing board, comprising a plurality of plane strips rigidly connected together at their adjacent edges and with one of said strips provided with an elongated opening extending longitudinally therethrough adjacent one edge, cleats extending transversely of the body, and rigidly connected with the strip opposite the strip provided with an elongated opening, and a bar extending through the elongated opening and connecting the cleats.

3. A drawing board comprising a body composed of a plurality of plane strips rigidly connected together at their adjacent edges, and one of said strips provided with an elongated opening extending longitudinally therethrough adjacent one edge, cleats ex-

tending along the end of the associated strips and associated therewith by tongue and groove connection, means rigidly securing the cleats to the strip opposite the strip provided with the elongated opening, and a bar extending through the elongated opening and connecting the ends of the cleats.

In testimony whereof I affix my signature in presence of witnesses.

GEORGE S. MANUEL.

Witnesses:

J. K. MANUEL,
